UNITED STATES PATENT OFFICE.

MAX GUNDELACH, OF GEHLBERG, GERMANY.

ANTICATHODE FOR RÖNTGEN-RAY TUBES.

Specification of Letters Patent. Patented Feb. 1, 1916.

1,170,247.

Application filed April 21, 1915. Serial No. 22,952.

To all whom it may concern:

Be it known that I, MAX GUNDELACH, a subject of the German Emperor, residing at Gehlberg, Duchy of Saxe-Coburg-Gotha, 5 Germany, have invented certain new and useful Improvements in Anticathodes for Röntgen-Ray Tubes, of which the following is a specification.

This invention relates to improvements 10 in anticathodes for Röntgen-ray tubes and is due to the discovery that metallic uranium, when employed as the anticathode in a Röntgen-ray tube, radiates rays which possess a far greater penetrating and radio- 15 scopic power than the rays produced by anticathodes made of the metals hitherto in use.

The present invention resides in the utilization of the above-mentioned, recently dis- 20 covered peculiarity of the metallic uranium.

An important advantage arising from 25 the use of metallic uranium is that it pos- sses a melting point close to that of tung- sten, and, when in pure state, it has a melting point even higher than that of tungsten, so that anticathodes constructed, accord- 30 ing to this invention, partly or entirely, of me- tallic uranium are, so far as their fusibility is concerned, at least equal to anticathodes

of tungsten, while they are, so far as the 30 penetrating power of their rays is con- cerned, far superior to anticathodes con- 35 structed of the metals hitherto in use. In consequence of their great penetrating power Röntgen-ray tubes having anticath- 40 odes of uranium are especially adapted for the radiosscopic treatment of carcino- mata, lues and the like.

In the annexed drawing, which is a view 45 in perspective of a Röntgen-ray tube em- bodying my invention, A represents the tube proper and B the anticathode made wholly or in part of metallic uranium.

What I claim is:-

1. In a Röntgen-ray tube, an anticathode 45 consisting partly of metallic uranium, sub- stantially as set forth.

2. In a Röntgen-ray tube, an anticathode 50 consisting entirely of metallic uranium, sub- stantially as set forth and for the purpose 50 specified.

In testimony whereof I have hereunto set my hand in presence of two subscribing witnesses.

MAX GUNDELACH.
